UNITED STATES PATENT OFFICE.

ARTHUR O. AUSTIN, OF BARBERTON, OHIO, ASSIGNOR, BY MESNE ASSIGNMENTS, TO THE OHIO BRASS COMPANY, OF MANSFIELD, OHIO, A CORPORATION OF NEW JERSEY.

HIGH-TENSION INSTALLATION.

Original application filed October 20, 1921, Serial No. 508,933. Divided and this application filed May 4, 1925. Serial No. 27,691.

This invention relates to installations for high electrical potentials, such as high tension transmission lines, wireless apparatus, and other constructions, and has for its object the provision of mechanism of the class named which shall be of improved construction and operation and which shall reduce the tendency to discharge of various characters from the highly charged conductors through the control of the electrostatic flux in the medium surrounding such conductors.

The invention is exemplified in the combination and arrangement of parts shown in the accompanying drawings and described in the following specification, and it is more particularly pointed out in the appended claims.

This is a division of application, Serial No. 508,933, filed October 20, 1921, Patent Number 1,664,100, issued May 27, 1928.

In the drawings—

Fig. 1 is an elevation of an installation embodying one form of the present invention;

Fig. 2 is a view similar to Fig. 1 of a slightly modified construction;

Fig. 3 is a section on line 3—3 of Fig. 2;

Fig. 4 is a section on line 4—4 of Fig. 2; and

Fig. 5 is a view similar to Fig. 1 of another form of the invention.

In high tension insulators for transmission and radio work as customarily used, a six or eight section suspension insulator will ordinarily withstand a greater voltage at a high frequency without danger of arcing than will the conductor on which the voltage is impressed, unless the conductor is of abnormally large size. It is, of course, not economical to use a conductor which is so large that the first cost and interest on the investment will be excessive, therefore abnormally large conductors are not feasible. Even if there were sufficient power to warrant a very large conductor for transmitting power at a high voltage, the line reactance due to the large current necessary for economy would be too great to permit of a size sufficiently large to prevent arcing of the conductor in the vicinity of the supporting tower where the electrostatic field is strong.

Spreading or splitting the conductor into several parts so as to increase the effective diameter would be of material benefit, but this is open to serious mechanical objections when carried out throughout the line or in the vicinity of the tower.

The insulators or portion of insulators next the transmission lines carry higher electrostatic stress than those farther from the line due to what may be termed the leakage of electrostatic flux to ground from different members in the series. The use of a very large conductor in the vicinity of the insulator tends to prevent or make up for this loss of electrostatic flux, thereby greatly improving the stress distribution or gradient for the insulating member or members. The gradient or stress distribution in the series may be improved by horns or flux controls, as shown in my previous Patent Number 1,552,664, issued September 8, 1925, or by a large ring or shield. Where a ring or shield is used to control the flux this ring or shield may lower the flashover owing to its projecting into a strong field on the tower side so that it may more than offset the advantage of an improved gradient in the insulator.

An eight or ten section insulator of good design will usually withstand a higher voltage than that which will start an arc from the conductor to the tower, a distance of from five to ten feet, depending upon electrical conditions, although the length of the insulator may be only half this value. From this it will be seen that using a long string of insulators may be of little benefit in providing a larger factor of safety, as an arc may start from the conductor to the tower. This invention is designed to prevent this arcing from conductor to tower by raising the voltage to which arcing or pluming will occur and at the same time reduce the danger of arcing of the insulator string by improving the distribution of stress in same.

Owing to the comparatively small diameter of the conductor and the comparatively short distance to the tower, there is a very strong field about the conductor in the vicinity of the tower so that by increasing the ef-

fective diameter of the conductor by means of a properly formed shield or screen running along or adjacent to the conductor, the stress in the air is lowered and the corona 5 point or voltage necessary to start a plume or arc may be greatly raised and the danger of pluming or arcing to ground under high frequency disturbances may be greatly reduced or eliminated.

10 There are two classes of discharge into the air from insulators or high voltage conductors. One class affects the performance of transmission lines very seriously due to the 15 arcing to ground at voltages much lower than would be indicated by the voltage which can be carried at normal frequency. Where a discharge from a conductor into the air is in the nature of a small streamer, the resistance of the streamer will be greatly reduced by 20 increasing the current in the same. As this current may be regarded as a charging current the air acting as a dielectric in a condenser and a streamer as one of the conducting plates, it will be seen that by increasing 25 the frequency the current in the streamer will be increased accordingly. Since, however, increasing the current in the streamer greatly reduces its resistance, the voltage drop along the streamer will be less, consequently the 30 high stress of the conductor will be carried out further from the conductor. This will cause a further break-down of the air, permitting an increase in the electrostatic capacity of the condenser which affects the current and resistance of the streamer acting 35 as one of the electrodes of the condenser. This further increase in current again reduces the resistance so that an accumulated effect is produced which is very serious when 40 a high frequency is impressed upon the line or insulator. This may be better understood when we consider that doubling the current in the streamer may cut its resistance in half.

From this it will be seen that while the 45 resistance in a streamer might be excessively high at a normal frequency of twenty-five or sixty cycles, the same length of streamer would have almost a negligible resistance if the frequency is increased several thousand 50 times, which might easily occur on the transmission line. This increase in frequency over the normal frequency may come from a number of different causes, such as lightning and arcing ground, the effect of corona on the line 55 in producing a harmonic, the harmonics produced by connected apparatus, or other causes. A discharge then which will cascade because of the accumulative effect of current, either due to the reaching of a sufficiently 60 high voltage, or partially due to the increased current from an increased frequency, or a combination of both, may cause serious arcing or at least arcing to ground at voltages much lower than would otherwise be the case.

A small diameter of conductor, as was 65 pointed out, permits a highly concentrated field which tends to produce streamers at comparatively low voltages. These streamers may exist at or even below the normal transmitting frequency. While there may be no 70 trouble from the same other than the loss of power at normal frequency, an increase in frequency, particularly when attended by an increase in voltage, may permit of the growth 75 of a streamer resulting in an arc to ground, as previously explained. Where the size of the conductor is increased the concentration of the field is reduced, and even though a streamer starts, the accumulative effect will not be so great and a much higher voltage and 80 frequency may be impressed without producing a plume or arc which will go to ground under a disturbance, permitting the energy 85 of the line to follow.

In Fig. 1 is shown a suspension string of 90 insulators 1 supporting a conductor 2 by means of a saddle 3. The effective diameter of the conductor in the vicinity of the insulator and tower is increased by a metallic cage 4 supported by a bar 5 secured to the saddle 3 at 6 and connecting with the conductor 2 at 7. The cage 4 may be made of wire or other suitable material wound in the form of a helix and extends for some distance along the conductor 2 away from the insulator 1. The cages 4 are made in duplicate 95 extending in both directions from the insulator without causing the ends of the cages to interfere with one another. Suspended from the bar 5 and the conductor 2 at spaced 100 intervals is a series of flux control members 9 which consists of metallic clamps secured to the conductor 2 and the support 5 and extending downwardly therefrom, the lower 105 ends of the downwardly extending portions being covered by insulators 10 to provide insulated flux distributors. In this figure the cage 4 is shown as surrounding the conductor, but in some cases it may be advisable to place the cage adjacent to the conductor or 110 to one side, or the conductor may be used to form part of the cage itself. It will be readily seen that this cage greatly increases 115 the effective diameter of the conductor so that a much higher voltage must be impressed to cause a sufficient concentration of stress in the air to start a streamer than in the case of a relatively small diameter of a bar conductor. The suspension string of insulators, being made up of a series of condensers, one 120 end of which is connected to the conductor, sets up an electrostatic field. This electrostatic field produced by the insulator approximating the voltage of the conductor improves the air gradient in its vicinity and 125 will tend to prevent streamers starting in the immediate vicinity of the insulator.

As the potential of the insulator approxi-

mates that in a streamer tending to start an arc, there will be a tendency to cause repulsion due to the well-known electrostatic law of repulsion of like charges. This repulsion 5 will be increased for a streamer starting from the conductor as the potential in the insulator string approximates that of the conductor. As previously explained, the conductor cage 4 being of much larger diameter than the 10 conductor 2 exerts a much greater effect on the electrostatic distribution of stress in the spring, the larger diameter tending to carry the conductor potential higher up in the string, thereby tending to reduce the current 15 in a streamer starting near the insulator. Furthermore, if a streamer is started the tendency to carry the conductor potential higher up in the string will produce greater electrostatic repulsion for the arc or streamer tending to keep same away from the insulator. 20 This latter is important for if the energy in the arc following the discharge to ground takes place over the insulator, the insulator may be seriously damaged, whereas if the arc 25 can be kept away from the insulator, little or no damage may result other than a momentary interruption of service to permit the arc in the air to die out. From the above it will be seen that the increase in diameter due to 30 the cage or conductor guard may be very beneficial in raising the voltage which it is possible to carry by a conductor or insulator string without arcing to ground.

In the installation shown in Fig. 1, a conductor arm 11 extending transversely of the line 2 carries an insulator 12 surrounding its outer end. This construction provides an insulated flux control member to control the field, particularly near the lower part of the 40 insulator. Any desired number of these control members may be used and may extend in different directions from the saddle 3. This flux control improves the electrical gradient in the insulator string and lowers the 45 air gradient around the clamp and insulator fittings. By improving the field and lowering the current in the streamers tending to discharge or plume at the clamp or insulator fittings, the flashover of the combination is 50 raised from approximately 350 k. v. to 460 k. v. By shielding the conductor on each side of the insulator string in the vicinity of the tower by the metal cage 4, the flashover of the combination will be raised to approximately 55 545 k. v. from which it will be seen that by the use of the insulated flux control and the cage on the conductor, the flashover will be raised from 350 k. v. to 545 k. v. or approximately 56% increase without increasing the 60 size of the insulator or the tower clearance.

If the insulator string is used with a larger or more expensive insulated flux control, the flashover voltage may be raised from approximately 350 k. v. to approximately 490 k. v. 65 The voltage cannot be raised further by in-

sulated flux controls in the immediate vicinity of the insulator string for an arc will start from the conductor two or three feet from the insulator string and go to the cross-arm or body of the tower or supporting structure. 70 As the flashover obtained with the cage 4 and the smaller insulated control was approximately 545 k. v. it will be seen that the conductor screen increases the flashover from 490 k. v. to 545 k. v. This higher flashover 75 which cannot exceed 490 k. v. without screening or caging the conductor in the vicinity of the tower is made possible by the use of the cage 4, which in addition improves the stress distribution in the insulator string, and 80 in some cases may permit the high flashover without the use of insulated control or other control devices to control the gradient in the insulator or the field in the vicinity of the insulator. 85

This improving of the stress distribution tends to permit the operation of the insulator at a higher voltage and also sets up a stronger field which tends to prevent the formation of an arc or plume in the vicinity of the insulator and while an arc is forming tends to repel same, as explained above. From the above it will be seen that caging the conductor not only raises the pluming point of the conductor in the vicinity of the tower where the 90 field is stronger than out on the line, thus permitting a higher applied voltage without arcing to ground, but in addition the stress distribution of the insulator string is improved. Furthermore, the cage may be so 100 made so as to protect the conductor from power arcs which might seriously damage the same. The use of the cage has a further advantage in greatly increasing the flashover under high frequency disturbances where the tower clearance is small. The use of the cage will permit a given flashover, particularly under high frequency conditions with much smaller tower clearance or in a stronger field than is possible without guarding the conductor, thereby permitting considerable saving in the cost of supporting structures. 105

The use of the conductor guard is not necessarily confined to suspension insulators, but may be very efficient in improving the distribution of stress in a strain or dead-end insulator and in raising the arcing or pluming voltage of the jumper connecting the two dead-end strings on either side of the tower. The conductor cage may be made in a variety 115 of forms, and the size of the spiral or cage and its relation to the conductor may be varied so as to develop the maximum flashover for a given position of a conductor. In Fig. 1 the relative position of the cage and conductor may be controlled by the supporting bar 5 and the clamping members 9. By making the conductor guard of open construction, the concentration of drip water 120 is eliminated and the cost of the guard kept 130

down. The concentration of drip water, if permitted, would tend to form a conducting path which would start a plume and lower the flashover, particularly where the cage or guard has a large projecting surface, which accumulates and concentrates considerable drip water. Where the conductor guard is made of a solid member, such as a tube of sheet metal, it is advisable to corrugate or perforate the guard so that the drip water will not be concentrated. The conductor cage may be so made that it will not only improve the gradient of the conductor in the vicinity of the tower, thereby raising its flashover, but will improve the stress distribution in the insulator string, and further can be made to protect the conductor from damage by power arcs, and can be so formed and installed as to eliminate serious discharge from the clamping or other insulator attachments. The use of the conductor guard permits higher operating voltages and frequencies without arcing from insulators, conductors and fittings from a given tower clearance, which will permit smaller clearance and thereby effect a considerable saving. The cage may so improve the stress distribution and flashover values of the combination that the use of the insulators in the string having different relative electrostatic capacities can be eliminated where a fine distribution of stress is desired. This would permit the use of one insulator throughout the string with its attended advantages as regards first cost and maintenance. Where it is desired to raise the voltage after an installation is made it frequently occurs that there is not sufficient clearance to permit an insulator of sufficient size without reducing the clearance so that arcing will occur. It will be seen that the conductor guard is of particular advantage in a case of this kind as it permits an increase in the voltage without danger of arcing, such as would occur in ordinary construction, due not only to high pluming voltage of the conductor, but also to the greater efficiency of the insulator permitting a shorter insulator with greater clearance.

The construction shown in Figs. 2, 3 and 4 is somewhat similar to that shown in Fig. 1, except that in this case a series of brackets or spiders 23 and 24 are distributed along the conductor 2 and carry at their outer ends a plurality of bars 25 which retain the coil 26 in fixed position relative to the conductor 2. By controlling the spacing of the coil 26 from the conductor the strength of the field surrounding the conductor may be correspondingly controlled for different positions to best protect it for particular installations.

In the form of the invention shown in Fig. 5, a tubular member 38 is spirally wound around the conductor 2, one end of the member being secured to the supporting saddle at

40 and the other end being attached to the cable 2 by a clamp 39. Supporting brackets 41 may be provided at intermediate positions as required.

I claim:

1. The combination with a high potential transmission line, and a series of connected loops of conducting material surrounding said line and electrically connected therewith and spaced from one another to provide an openwork cage extending longitudinally of said line.

2. The combination with a transmission line, having a support, of an openwork cage disposed adjacent said support and extending longitudinally of said line, said cage comprising an elongated member of conducting material wound in a helix about said transmission line.

3. The combination with a high potential transmission line, having a support, of an openwork cage extending longitudinally of said transmission line adjacent said support, said cage comprising an elongated conductor wound in a helix about said transmission line, and means for supporting said conductor on said line.

4. The combination with a high potential transmission line, having a support, of a flux controlling cage extending along said transmission line adjacent said support, said cage comprising an elongated member of conducting material wound in a helix about said transmission line, and a support intermediate the ends of said cage for holding said cage in spaced relation with said line.

5. The combination with a high potential transmission line, having a support, of a supporting rib adjacent said support extending longitudinally of said line and spaced therefrom, and a helically wound conductor supported by said rib and disposed about said transmission line.

6. The combination with a high potential transmission line, of a pair of spaced brackets mounted on said line, ribs carried by said brackets in spaced relation to said line, and an elongated conductor wound in a helix about said ribs and line.

7. The combination with a high potential transmission line, having a support, of spaced brackets mounted on said line adjacent said support, supporting ribs extending longitudinally of said line and secured to said brackets, and an elongated member of conducting material wound in a helix upon said ribs.

8. The combination with a high potential transmission line, having a support, of a helix of conducting material surrounding said line and having one end disposed adjacent said support, the opposite end of said helix being tapered toward said transmission line and attached thereto.

9. The combination with a high potential transmission line, having a support, of brackets attached to said line, a supporting rib carried by said brackets and having one end thereof adjacent said support and the opposite end thereof inclined toward said line, a member having a rounded outer surface for connecting said inclined end to said line, and a helix of conducting material wound about said rib and line and extending from said insulator to said connecting member.
- In testimony whereof I have signed my name to this specification on this 27th day of April, A. D. 1925.

ARTHUR O. AUSTIN.
